[57] **CLAIM**

The ornamental design for the write protect slide, as shown and described.

DESCRIPTION

FIG. 1 is a three-quarters isometric view of our new design from the front right corner of the slide;

FIG. 2 is a top plan view;

FIG. 3 is a rear view, on an enlarged scale;

FIG. 4 is a left side view;

FIG. 5 is a front view, on an enlarged scale;

FIG. 6 is a right side view;

FIG. 7 is a bottom plan view; and,

FIG. 8 is a three-quarters perspective view of our new design, on a reduced scale, with a broken line drawing of a portion of a tape cartridge provided for illustrative purposes only and forming no part of the claimed design.
